GAME BOARD

James P. Tillmann, 5916 63rd Ave. N.,
Brooklyn Park, Minn. 55429

Filed Feb. 20, 1969, Ser. No. 15,852

Term of patent 14 years

Int. Cl. D21—01

U.S. Cl. D34—5

The figure is a plan view of a game board showing my new design. The board is of conventional thickness, and is lined to indicate contrasting color.

I claim:

The ornamental design for a game board, substantially as shown and described.
